UNITED STATES PATENT OFFICE.

DAVID LOGAN BISSET, OF MONTREAL, QUEBEC, CANADA.

CHUCK.

1,392,109.

Specification of Letters Patent. Patented Sept. 27, 1921.

Application filed January 17, 1920. Serial No. 352,157.

To all whom it may concern:

Be it known that I, DAVID LOGAN BISSET, a subject of the King of Great Britain, and residing at 75 Columbia avenue, in the city 5 and District of Montreal, in the Province of Quebec, in the Dominion of Canada, have invented a new and useful Chuck, of which the following is the specification.

The invention relates to chucks as described in the present specification and illustrated in the accompanying drawings that form part of the same.

The invention consists essentially in the novel means employed for housing the gripping jaws, whereby the force employed in boring the work adds to the security of the fastening.

The objects of the invention are to efficiently hold the boring tool in its place during boring operations; to facilitate the adjustment of the jaws; to insure simplicity in the construction and materially improve the conditions in regard to repairs and replacements; and generally to provide safety and durability in the operation of boring tools.

In the drawings, Figure 1 is a longitudinal sectional view, showing the jaw housing and jaws with a drill inserted therein.

Fig. 2 is a cross sectional view on the line 30 A—A in Fig. 1.

Fig. 3 is a cross sectional view on the line B—B in Fig. 1.

Fig. 4 is a cross sectional view on the line C—C in Fig. 1.

Fig. 5 is a detail of the jaw expansion spring.

Fig. 6 is a perspective detail of the adjusting head.

Fig. 7 is a perspective detail of the outer 40 adjusting sleeve.

Fig. 8 is a perspective detail of the jaws.

Like numerals of reference indicate corresponding parts in each figure.

Referring to the drawings, the body 1 of 45 the chuck forms part with the shank 2 or any other piece for securing it to the machine, such as a socket or the like. The annular rib 3 is formed on the body 1, adjacent to the inner shank end, and the central tapered jaw recess 4 extends inwardly from the outer end. The threaded hole 5 is made in the wall of said recess and the squared shoulder of the annular rib 3 forms a retaining ring for the outer adjusting sleeve 6, the 55 latter having an inturned flanged end 7 over said shoulder.

The sleeve 6 beyond the rib 3 is internally threaded at 8 to its extremity and its periphery 9 is knurled.

The jaws 10, 11 and 12 form three parts 60 and together taper from the center to the ends in double cone shape having at the inner ends the flanges 13 made to receive the flat end of the shank 2.

The jaws 10, 11 and 12, each have a spring 65 recess 14 intermediate of the length thereof and slightly beyond the center of the jaws toward the outer end, and the expansion spring 15 is inserted in said recesses when the jaws are assembled in the recess 4.

The chuck head 16 is formed with the tapered jaw opening 17 and the cylindrical extension 18 externally threaded and is screwed into the adjusting sleeve 6, longitudinally slotted at 19 to receive the screw 20 75 which fastens in the body 1 and in contact with the walls of the slot 19 keeps both the extension head and adjusting sleeve from rotating in respect to the body.

In the operation of this chuck, the double 80 cone jaws are assembled in the jaw recess of the body 1 and in their taper conform to the shape of said jaw recess. The chuck head 16 is closely fitted to the outer cone portion of the jaw and the jaw opening in said chuck 85 head corresponds to the taper of said outer portion. The screw 20 is screw threaded into the hole 5 through the slot 19, therefore the body and the chuck head are secure from rotation in relation to one another and the 90 adjusting sleeve, that is to say, all must rotate together.

The adjusting sleeve 6 is then screwed on to the chuck head 16 and the jaw opening 17 is adjusted to the drill or other boring tool, 95 which may be inserted.

The tool is then ready for use and the shank inserted in the machine, or if it is a socket a spindle from the machine is inserted in the socket, for that is no part of the invention, and as soon as this is done and the tool applied to the work, it will be seen that the greater the force employed, the closer the jaws will grip the drill, up to the limit of their gripping properties, therefore 100 the drill or other boring or finishing tool will always be held securely and firmly to the work and in the chuck and no matter whether the work is done on a drilling machine, lathe or boring mill, the effect of the grip will be 105 precisely the same.

Many changes may be made in the details

of the construction of this tool without departing from the spirit of the invention, and so long as these changes are within the scope of the claim for novelty following, the protection accorded shall not be invalidated.

What I claim is:—

In a chuck, in combination, a jaw socket member having a tapered recess in the cylindrical body portion, and an annular flange adjacent to the inner end of said body, a plurality of jaw members together forming a double cone shaped shank holder tapering from the central portion to the ends, one tapered portion being inserted in said jaw recess and the other projecting outwardly

therefrom and spring-held apart, a chuck head forming a jaw-contracting member, having a tapered mouth engaging said outwardly projecting tapered portion, and a barrel extension slidably and non-rotatably arranged on said body and externally threaded, and an operating sleeve internally threaded and engaging said barrel extension of the chuck head and rotatable on said annular flange.

Signed at the city of Montreal, Province of Quebec, Dominion of Canada, this 10th day of January, 1920.

DAVID LOGAN BISSET.
